CLAIM

The ornamental design for a jaw for a surgical instrument, as shown and described.

DESCRIPTION

FIG. 1 is a perspective view of a jaw for a surgical instrument in accordance with the new design;

FIG. 2 is a front view of the jaw for a surgical instrument of FIG. 1;

FIG. 3 is a rear view of the jaw for a surgical instrument of FIG. 1;

FIG. 4 is a right side view of the jaw for a surgical instrument of FIG. 1;

FIG. 5 is a left side view of the jaw for a surgical instrument of FIG. 1;

FIG. 6 is a top plan view of the jaw for a surgical instrument of FIG. 1; and,

FIG. 7 is a bottom plan view of the jaw for a surgical instrument of FIG. 1.

The even length broken lines in the figures are directed to portions of the jaw for a surgical instrument that form no part of the claimed design. The dot-dashed lines show unclaimed boundaries and form no part of the claimed design.
